UNITED STATES PATENT OFFICE

141,986

DESIGN FOR A HANDBAG

Herbert Rubin, Chicago, Ill.

Application January 1, 1945, Serial No. 117,205

Term of patent 7 years

(Cl. D87—3)

To all whom it may concern:

Be it known that I, Herbert Rubin, a citizen of the United States, residing in Chicago, in the county of Cook and State of Illinois, have invented a new, original, and ornamental Design for a Handbag, of which the following is a specification, reference being had to the accompanying drawing, forming part thereof.

Fig. 1 is a elevational front view of a handbag showing my design.

Fig. 2 is the rear view of the handbag shown in Fig. 1.

Fig. 3 is an edge plan view of the handbag shown in Figs. 1 and 2, and

Fig. 4 is a fragmentary view thereof in partially opened position.

I claim:

The ornamental design for a handbag, substantially as shown.

HERBERT RUBIN.
